[57] **CLAIM**

The ornamental design for a toy clock and radio, as shown and described.

DESCRIPTION

FIG. 1 is a top left front perspective view of a toy clock and radio showing my new design;

FIG. 2 is a front elevational view thereof;

FIG. 3 is a rear elevational view thereof;

FIG. 4 is a top plan view thereof; and,

FIG. 5 is a right side elevational view thereof.

The broken line showing is environmental only and forms no part of the claimed design.
